(57) **CLAIM**

The ornamental design for a X-ray apparatus for medical treatment, as shown and described.

DESCRIPTION

FIG. 1 is a front, top and right side perspective view of a X-ray apparatus for medical treatment, showing our new design; FIG. 2 is a rear, top and left side perspective view thereof; FIG. 3 is a front view thereof; FIG. 4 is a rear view thereof; FIG. 5 is a top view thereof; FIG. 6 is a bottom view thereof; FIG. 7 is a left side view thereof; FIG. 8 is a right side view thereof; FIG. 9 is a cross sectional view thereof, taken along the line 9-9 in FIG. 3 with its internal mechanisms omitted; and, FIG. 10 is a reduced front view thereof, showing the state of the slide rail, which is rotated along the arc. The broken lines are for illustrative purpose only and form no part of the claimed design.
